UNITED STATES PATENT OFFICE.

JACOB F. BAHRET, OF FORT WAYNE, INDIANA.

TOY TRUNDLE OR HOOP.

SPECIFICATION forming part of Letters Patent No. 276,746, dated May 1, 1883.

Application filed March 3, 1883. (Model.)

To all whom it may concern:

Be it known that I, JACOB F. BAHRET, of Fort Wayne, county of Allen, and in the State of Indiana, have invented certain new and useful Improvements in Toy Trundles or Hoops; and I do hereby declare that the following is a full, clear, and exact description thereof, reference being had to the accompanying drawings, and to the letters of reference marked *o* thereon, making a part of this specification.

This invention has for its objects to provide an improved toy running hoop or trundle for children, which can be easily managed by any child, and which, when in motion, by reason *15* of its peculiar construction, will present a pleasing appearance, as more fully hereinafter specified.

The above-mentioned objects I attain by the means illustrated in the accompanying drawings, in which—

Figure 1 represents a perspective view of my invention, and Fig. 2 is a detail sectional view.

The letter A indicates a hoop or wheel having two sets of curved spokes, A', one at each side, as indicated. These spokes are arranged to turn freely on a short shaft or sleeve, B, through which is passed the bifurcated frame C, which straddles the wheel, and is provided *25* with a handle, D, as shown. Within the wheel A, between the spokes and attached to the shaft or sleeve B, is a stationary wheel, E, having curved spokes F, the said spokes turning in a direction opposite to the spokes of the *30* wheel A. Between the spokes of the wheel A and the shoulders on the shaft or axle are in-

terposed the washers G to keep the spokes on the large wheel at an equal distance from the center.

The operation of my invention will be readily *40* understood in connection with the above description, and is as follows: The toy is seized by the handle, and the hoop placed upon the ground and pushed forward by the child rotating the large wheel while the small wheel *45* remains stationary. The spokes of the respective wheels being curved in opposite directions and painted in different colors, as the larger wheel moves and causes its spokes to pass those of the smaller wheel, a pleasing *50* combination of colors and an agreeable effect are produced.

Having thus described my invention, what I claim, and desire to secure by Letters Patent, is—

A toy hoop or trundle consisting of a revolving wheel mounted upon a short shaft, and provided with curved spokes on opposite sides, a smaller non-revolving wheel mounted upon the same shaft and having spokes curved in the *60* opposite direction, the respective sets of spokes being differently colored, and the bifurcated frame and handle, the whole arranged to operate substantially in the manner specified.

In testimony whereof I affix my signature, in *65* presence of three witnesses, this 4th day of September, 1882.

JACOB F. BAHRET.
